UNITED STATES PATENT OFFICE

105,285

DESIGN FOR A DRESS ENSEMBLE

Jack Kirschner, New York, N. Y.

Application June 14, 1937, Serial No. 69,820

Term of patent 3½ years

To all whom it may concern:

Be it known that I, Jack Kirschner, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

The sleeves of the dress unit are identical in shape to the sleeves of the jacket unit.

The rear portion of the dress unit is conventional.

I claim:

The ornamental design for a dress ensemble, substantially as shown, and described.

JACK KIRSCHNER.
